AUTOMATIC FEED FOR BORING BARS

Clarence T. Rottler, Seattle, Wash.

Application March 25, 1936, Serial No. 70,857

14 Claims. (Cl. 77—2)

My invention relates to boring bars, that is, machines usually employed in reborning the cylinders of internal combustion engines, of the general type illustrated in my Patent No. 5 2,011,875.

It is particularly an object of the present invention to provide means controlling movement of the boring bar whereby it may be fed slowly downward, moved upward, or moved downward rapidly, and whereby all such movements may be either necessarily under control of the operator, or under control of elements which will automatically stop or reverse the movement of the boring bar upon completion of a predetermined 15 amount of such movement, to the end that the operation of the boring bar may be made substantially automatic.

The term "feeding", as herein used, shall be taken to mean "movement", whether during 20 cutting operation of the boring bar's tool bit, or otherwise.

It is a further object to provide automatic control mechanism for slow downward feed which may be readily adjustable in accordance with 25 the depth of the cylinder upon which the boring bar is operating.

It is a further object to provide interlocking mechanism and such arrangement of the several controls that one control only may function at a 30 time, to the end that there cannot be interference between two different drive mechanisms, each driven from the same source of power.

It is a further object to devise control and feed mechanism of this general type which can be 35 thrown into a neutral or a nonoperative position at any time, as for example, in an emergency, to stop all feeding movement of the boring bar.

More specifically, it is an object to devise control mechanism which may be positioned in a 40 given position to accomplish downward feed of the boring bar, and adjustable automatic reversing mechanism cooperating therewith which, at the predetermined limit of downward movement of the boring bar, will automatically reverse 45 the control mechanism to commence upward movement of the boring bar, and further, to devise means which upon the completion of the upward movement of the boring bar will automatically throw the control mechanism into neutral position, thereby stopping movement of the boring bar, and holding it in its uppermost position.

It is also an object to provide latching mechanism to hold such controls in either position, which latch mechanism is automatically disengaged upon the boring bar reaching either the

upward or downward limit of its movement, in order that reversal thereof, or the throwing of the same into neutral position, may be accomplished.

It is a further object to simplify the driving mechanism of such a boring bar, and to condense it into the smallest practicable space, to the end that the boring bar may be neat and compact, and of weight sufficiently low that it may readily be moved from place to place, as 10 required.

It is a further object to devise an accurate boring bar, yet one wherein the component parts need not be finished or fitted with extreme accuracy, thereby lessening the cost of production 15 and the liability to get out of order.

It is an object to devise mechanism which will insure rotation of the screw and nut at identical speeds, when the control mechanism is in neutral position, so that there will be no tendency for the boring bar to move up and down, when it is intended that it shall stand still. This makes possible the use of a tool-lapping arrangement disclosed and claimed in my copending application Serial No. 70,858, filed March 25, 1936. 25

These and other objects will be better understood as the present specification progresses.

My invention comprises the novel boring bar and the novel arrangement and combination of the parts thereof, as shown in the accompanying 30 drawings, described in this specification, and as will be more particularly pointed out and defined by the claims which terminate the same.

In the accompanying drawings I have shown my invention incorporated in a preferred form of 35 boring bar, and in a form now preferred by me, it being understood, however, that such changes may be made in the form, proportion and arrangement of the parts, within this disclosure, as may be included within the claims.

Figure 1 is an elevation of the boring bar, parts being broken away, and the cylinder block being shown fragmentarily and in section.

Figure 2 is an elevation, with parts broken away, of the upper end of the boring bar, and 45 Figure 3 is a section through the same substantially on the line 3—3 of Figure 2.

Figures 4, 5 and 6 are transverse vertical sections through the head of the boring bar, taken on the respective lines 4—4, 5—5, and 6—6 of 50 Figure 2, Figures 5 and 6, however, showing parts in a different position than that illustrated in Figure 2.

Figure 7 is a detail section through the control handle and latching means.

40

40

55

The hollow boring bar 9 is vertically slidable in suitable bearings within a base 90, and on its lower end is rotatable a cutter head 91 carrying the fly cutter 92. Projectable fingers 93, movable 5 inwardly and outwardly at will, are also provided on the cutter head, and a rod 94, extending axially through the axial bore of the boring bar 9 and terminating in a handle 94', is rotatable to control projection and retraction of the fingers 93, and is vertically movable to control projection and retraction of the tool 92. A handle or lever 99 enables manual lifting of the rod 94 when required.

A motor 95 is preferably mounted upon the base, and extending upwardly from and geared to the motor, to be rotated thereby, is a shaft 96. This is journaled in the base and extends through the head 97, carried by the upper end of the boring bar 9 and constituting a gear casing. The shaft 96 is screw threaded (right-handed, and rotating in the direction of the arrow A in Figure 5, as shown) and terminates at its upper end in an enlarged handle 96'. These arrangements (other than the use of a screw which rotates in 20 the indicated direction, with relation to the direction of its thread) are not part of the present invention, but known in the prior art, and no further detailed description thereof is deemed necessary, nor is it deemed necessary to describe the anchor 4 in detail, this comprising a portion which is supported within a cylinder other than the one being worked upon by the cutter 92, and which is secured to the base 90 to hold it down upon the top of the cylinder block.

The drive arrangement for the boring bar is somewhat different from that shown in my patent referred to above, and will be described for better understanding of the invention. The screw threaded shaft 96 is longitudinally grooved as indicated at 96'' to receive a key 79 whereby a gear 7, which constitutes the driving gear, is secured to rotate with the shaft 96. Loosely mounted upon a sleeve 7' integral with the gear 7 is a gear 70, which has a slightly different number of teeth than the gear 7, preferably one more tooth, so that the two constitute differential gears. Both these gears mesh with a gear 71, and the gear 70 is provided with clutch elements 72 with which may be meshed complementary clutch elements 73 upon a slidable clutch sleeve 74. This sleeve 74 is keyed at 75 to a nut 76 threaded upon the threaded shaft 96.

The slidable clutch sleeve 74 is further provided with gear teeth 78, with which is meshed a gear 6. With the driving gear 7 is meshed a smaller gear 60, loose upon a stub shaft 61 and provided with clutch elements 62 capable of engaging with complementary clutch elements 63 upon the large gear 6. A spring pressed plunger 64 (see Figure 2), received in an axial bore of the stub shaft 61, normally holds the complementary clutch elements 62 and 63 out of engagement, but the two may be engaged by a yoke 58, acting through a lever 57 fulcrumed at 56 to press downward the pin 65, guided at 66 in the head 97, when the yoke 58 is raised (compare Figures 2 and 6), such raising of the yoke 58 being accomplished by raising the control handle 52, as will be later described in detail. As a result of engaging the clutch elements 62 and 63, the head 97 and the boring bar are moved rapidly upward.

Control of the engagement and disengagement of clutch elements 73 and 72, and of clutch elements 63 with 62, may be accomplished by a rock shaft 5 (see Figures 2, 3, 4, and 6), which is piv-

otally received in the interior of the head 97, and which may be rocked by the control handle 52. Fingers 50 on this rock shaft engage a collar 94'' on the rod 94 to raise it when the rock shaft 5 is suitably rocked, thus to effect or permit withdrawal of the tool 92 inwardly of the cutter head 91. Another finger 51 engages in a groove 74' of the member 74, whereby to control movement of the latter. When the control handle 52 is shifted upwardly the clutch elements 73 are disengaged from clutch elements 72, and when said handle is shifted downwardly 73 is engaged with 72. Upward movement of the control handle 52 engages the clutch elements 63 and 62, and downward movement permits their disengagement, hence there can never be a tendency for downward slow feed (by engagement of 73 and 72) at the same time as fast upward feed (by engagement of 63 and 62).

If it is desired to effect downward feed of the 20 boring bar at a slow rate, the clutch elements 72 and 73 are engaged (see Figure 5) by downward movement of the control handle 52, as indicated above. Note that this permits the rod 94 to be lowered, and this lowering movement, by means 25 not shown, but known in the art, effects outward projection of the tool 92 to the diameter of the cylinder to be cut. With the clutch elements 72 and 73 engaged, rotation of the shaft 96 through the key 79 rotates the driving gear 7, which in 30 turn rotates the idler gear 71, and this rotates the gear 70. In turn the sleeve 74 is rotated by the engagement of the clutch elements 72 and 73, and the sleeve 74, being keyed to the nut 76, 35 rotates the latter, but since the gears 7 and 70 40 contain a different number of teeth, they will rotate at a slightly differential rate, so that while the shaft 96 and the nut 76 both rotate, their rate of rotation will be different, and the combination will effect downward feed of the boring 45 bar at a slow rate. Meantime the cutter head 91 is being rotated, since the gear 71, driven from the driving gear 7, is secured to the hollow shaft 71', passing through the axial bore of the boring head 91, and carrying the cutter head 91 at its 45 lower end.

When it is desired to move the boring bar upwardly, the slidable clutch elements 63 are shifted, as described above, into their lower position (compare Figures 2 and 6) to engage the 50 complementary clutch elements 62. This necessarily disengages clutch elements 73 and 72, and increases the rate of rotation of the sleeve 74 and consequently of the nut 76 keyed thereto, by reason of the difference in size of gears 60 and 6, 55 and since the screw 96 continues to rotate at the same rate, this will effect upward movement of the boring bar at a rapid rate.

If it is desired to effect more rapid downward movement of the boring bar, as, for example, 60 when using the centering fingers 93 to preliminarily align the axis of the boring bar with the axis of the cylinder, this may be accomplished by stopping rotation of the sleeve 74 and nut 76. This is readily accomplished by pressing inward 65 the button 8, against its spring 81, whereby its inner end 82 engages one of several notches 77 in the exterior of the sleeve 74. The nut 73 being thus held stationary, but the screw 96 continuing to rotate, the head 97 and the boring bar are 70 moved downward rapidly. As will be evident from inspection of Figure 5, engagement of pin 82 in a notch 77 can only occur when sleeve 74 is in a neutral position, at which time neither clutch 73 72, or 63, 62 is in engagement. Since 75

the pin 82 will only remain in engagement with 77 so long as it is pressed inward against the spring 81, it is assured that the operator will stand by, to prevent rapid downward feed to 5 progress further than is desired.

It will be seen from the above that the several clutch elements are so interconnected and arranged that there can not be engagement of any two sets of clutch elements at any one time.

10 The base 90 is provided with a boss 90' and a set screw 90'' (see Figure 1), in which is received a vertical rod 3. This rod, which is held by the bore to extend parallel to the axis of the boring bar 9, extends vertically upward, and its upper 15 end is axially bored, as indicated in Figure 5, to receive a compressible spring 30, holding upwardly a headed plunger 31. Also formed on the upper end of the rod 3 is a cam surface, in the shape of a cone 32. The plunger 31 is positioned 20 in the path of movement of the control handle 52, so that as the latter, moving with the head 97, approaches the desired lower limit of its movement, at which time the cutting tool 92 will have passed beyond the lower end of the cylinder 25 which it is reboring, the plunger will have been depressed by previous contact with the control handle 52, and the spring 30 will have been compressed. If the control handle 52 had been there- 30 tofore latched or held in its downward position, to accomplish downward feed of the boring bar, but is now unlatched or released, this compression of the spring 30, acting through the plunger 31, will throw the control handle 52 upwardly into position to engage the clutch elements 63 and 62, 35 thereby initiating upward movement of the boring bar.

In order to control the point of this reversal I provide latching means to hold the control handle 52 either in its downward position or in its upward position. Such latching means, best shown 40 in Figure 7, may comprise a square-headed stud 2 fixed in the casing 97, and a latch 20 formed as part of a lever 21 pivoted at 22 upon the outer end of the control handle 52. A spring 23 tends to hold the latch 20 in engagement with the stud 2. The lever 21 carries a finger 24 at its lower end, which will engage the cam or conical surface 32 upon compression of the spring 30 to a desired extent, and the lever 21 will thereby be rocked 45 to an extent to disengage the latch 20 from the stud 2, so that upon a predetermined amount of compression of the spring 30 the latching means will be disengaged, to throw the control handle 52 into its upper position, corresponding to upward feed of the boring bar, whereupon the latch 20 will engage the upper side of the stud 2, being 50 pressed inward by the spring 23, and upward movement of the boring bar will be effected. It will be seen that the point of disengagement and 55 reversal may be controlled by adjustment of the rod 30 vertically in its boss 90', and that it may be held in any adjusted position by the set screw 90''.

Upon reaching the upper limit of movement of 60 the boring bar a second finger 25 (see Figure 5) on the lever 21, positioned to engage beneath the head 96' on the screw 96, comes into engagement with the head 96', again rocking the lever 21 and disengaging the latch 20 from the stud 2, permitting 65 the control handle 52 to drop to its neutral position, where it is held by a spring 59 (see Figure 7).

To control movement of the handle 52 a finger button 26 may be provided on the lever 21, which 70 may be pressed upwardly or downwardly to ac-

complish corresponding movement of the boring bar, it being remembered that downward movement of the control handle 52 engages slow down feed clutch elements 73 and 72, and upward movement of the control handle engages fast up feed 5 clutch elements 63 and 62. Another finger button 27 may be provided on the lever 21, which when pressed or struck will always (as in an emergency) disengage the latch 20 from the stud 2, and permit the control handle 52 to return to its 10 neutral position, stopping all feed of the boring bar.

The rotative screw head 96' may be employed as a grinding and lapping tool, as disclosed in my companion application, Serial No. 70,858, referred 15 to above. In so doing the tool bit is held in a jig secured to the casing 97, and no variation in the vertical position of the head 96' relative to the casing 97 can be permitted. Using a left-handed thread, turning in the direction of the arrow A 20 (Figure 5), as in my Patent No. 2,011,875, I discovered that there was a tendency with the sleeve 74 in neutral position, for the casing 97 to move upwardly, then downwardly, with considerable fluctuation in load on the motor, indicating recurring friction in the machine. The upward movement, I discovered, was due to the tendency of the nut 76 to climb the screw 96, and to jam against the top of the casing 97, moving the latter upward, then, as the load on the motor, or the 30 movement of the casing, relieved or overcome the friction resisting rotation of the nut at the same speed as the screw, the casing would drop, and the upward movement would recur.

Merely to provide an antifriction bearing, as at 35 98, was found not to avoid this tendency, hence, by reversal of the direction of the screw threads (making it right-handed instead of left-handed), continuing the same direction of rotation of the screw, and making the differential gear 70 with 40 one (or more) tooth more than the driving gear 7, I found that the tendency for the nut 76 to climb up the screw while in neutral was converted into a tendency for it to move downward on the screw. While this might be considered 45 immaterial—its immovability with respect to the screw being the desideratum—it will be observed that any tendency for the nut to move downwardly will only result in a pressure of the nut on the extension 7' of the gear 7. Since the 50 latter is keyed to the screw and must rotate therewith, and as any pressure of the nut upon the gear 7 will tend to cause the two to rotate at the same speed, it follows that any such pressure only brings about the very result desired, without 55 any friction. The motor load is therefore steady and light, and the objectionable up and down movement of the casing 97 is completely overcome by this change.

Upward thrust from the nut to the casing 97, 60 such as occurs during upward feed of the boring bar, with the nut rotating in the same direction as and more rapidly than the screw, is taken by the antifriction bearing 98, and as the motor is free at such times from any other load, this is 65 unobjectionable. I have found that the present arrangement lessens the load on the motor during slow downward feed, when the fly cutter 92 is operating, in comparison to its load under the old arrangement. I attribute this to the fact 70 that the gear 70 and nut 76, both turning in the same direction as the gear 7 and bearing thereupon to produce the downward movement of the casing, are turning slightly slower than the gear 7, and the latter tends directly to pull the gear 75

70 and the nut 76, around, by this frictional action relieving the gearing of a large part of its load, and lessening the friction of the whole. It has been observed that this result occurs, and 5 this lessens wear and the motor load, hence lengthens the life and reliability of the entire boring bar. With the arrangement of my prior patent the differential gear and nut, rotating more rapidly than the main driving gear and 10 screw, and about a screw which was left-handed, tended to wedge the nut more tightly between the incline of the screw thread and the driving gear, thus producing more friction than in the present arrangement, hence a greater load on the 15 motor at a time when its maximum load was imposed.

What I claim as my invention is:

1. In a reboring machine, in combination with a base, a boring bar vertically reciprocable in the 20 base, and terminating at its upper end in a head constituting a gear casing, a power-driven screw journaled in the base and extending through the head, a nut threaded thereon, two differential gears, one constituting a driving gear and keyed 25 to the screw, and the other loose thereon, a common gear in mesh with each differential gear, a gear-toothed sleeve slidable along and keyed to rotate with the nut, a set of complementary clutch elements, one part on the loose gear and one part 30 on the sleeve, engageable by downward movement of said slidable sleeve to advance the boring bar slowly downward, a pair of gears of unequal diameter in mesh respectively with the driving gear and the sleeve's gear teeth, a second set of complementary clutch elements on the 35 unequal gears engageable when said sleeve is shifted upwardly, to rotate the nut at a different speed and in a different direction relative to the screw, thereby to effect upward movement of the 40 boring bar, a control handle shiftable upwardly or downwardly from a neutral position to control upward or downward shifting of the sleeve, and thereby the engagement of the respective clutch elements, a third set of clutch elements, one part 45 formed on the sleeve, the other part being fixedly positioned, the two parts being engageable to stop rotation of the nut, and to effect rapid downward movement of the boring bar, the last-mentioned clutch elements on the sleeve being disposed, 50 relative to the fixedly positioned clutch element, to be engaged only when the sleeve and its other clutch elements are in neutral position, thereby to interdict engagement of the last set of clutch elements except when the other two sets 55 of clutch elements are in neutral position.
2. In a reboring machine, in combination with a base, a boring bar vertically reciprocable in said base, power feed mechanism operatively connected to the boring bar to effect such reciprocation, including a continuously rotating driving gear, a clutch sleeve operatively connected at all 60 times to the feed mechanism for rotation therewith, and movable to and from clutch-engaged position, means operable to effect downward feed of the boring bar when the clutch sleeve is in such position, a gear formed on said clutch sleeve, of a diameter different from that of the driving gear, two differently sized, axially aligned gears meshing with the driving gear and with the 65 clutch sleeve gear, respectively, cooperating clutch elements to connect said aligned gears, yieldable means normally holding said clutch elements disengaged, means operable by such engagement of the said clutch elements to effect upward feed of the boring bar, and control means 70

common to the clutch sleeve and to the cooperating clutch elements, movable in one direction from a neutral position to place the clutch sleeve in clutch-engaged position for downward feed, and movable in the opposite direction from such neutral position to engage the cooperating clutch elements, thereby to effect upward feed of the boring bar. 5

3. In a reboring machine, in combination with a base, a boring bar vertically reciprocable in 10 said base, a power driven screw parallel to the boring bar, a driving gear carried by the boring bar and keyed to and movable axially along said screw, a differential gear coaxial with the driving gear and having a greater number of teeth, an 15 idler gear meshing with the driving and differential gears, whereby the former gains on the latter, a nut threaded on said screw, a clutch sleeve slidable on and connected to rotate with said nut, cooperative clutch elements formed on the clutch 20 sleeve and differential gear, the screw having such direction of thread and rotating in such direction that, when said clutch elements are engaged, the nut feeds the boring bar slowly downward, gear teeth formed on the clutch sleeve, 25 of less diameter than the driving gear, a pair of unequal coaxial gears, the smaller one meshing with the driving gear and the larger one with the sleeve gear, cooperating clutch elements to connect said pair of gears, whereby, when they 30 are engaged, to rotate the nut relatively to the screw in a direction to feed the boring bar rapidly upward, and selective means movable from a neutral position to engage the clutch sleeve with the differential gear or alternatively to engage the 35 two aligned gears, thereby to control the direction of feed of the boring bar.

4. In a reboring machine, in combination with a base, a boring bar vertically reciprocable in the base, power means for effecting such reciprocation, including a drive shaft and a clutch gear shiftable to effect slow feed downward, a second clutch gear meshed with said first clutch gear and shiftable to effect upward feed, drive means connecting each of said clutch gears, in clutch- 45 engaged position, with said drive shaft, and a rock shaft interengaged between said two clutch gears, and oscillatable in one direction to move said downward feed clutch gear from a neutral position, wherein neither clutch gear is operative, 50 into bar driving position, said upward feed clutch gear remaining in neutral position, and oscillatable in the opposite direction to move conjointly and simultaneously said downward feed clutch gear into neutral position and said upward feed 55 clutch gear into bar driving position.

5. In a reboring machine, in combination with a base, a boring bar vertically reciprocable in the base, and having a nonrotatable head, power means including two rotatable clutch elements, a 60 control element shiftable from a neutral position into either of two clutch-engaged positions for rotation by one or the other of said clutch elements, thus to effect either slow downward feed or upward feed of the boring bar, and a locking 65 member fixed in position on said nonrotatable head and movable into locking engagement with said control member only when the control element and the parts controlled thereby are in neutral position, to hold said control member from 70 rotation, thus to effect rapid downward movement of the head.

6. In a reboring machine, in combination with a base, a boring bar vertically reciprocable in the base, power means for effecting such recip- 75

5 rocation, including a clutch gear shiftable to effect low speed downward, a second clutch gear meshed with said first clutch gear and shiftable to effect upward feed, a rock shaft interengaged between said two clutch gears, and oscillatable in one direction to move said downward feed clutch gear from a neutral position into bar driving position, and oscillatable in the opposite direction to move simultaneously said downward

10 feed clutch gear into neutral position and said upward feed clutch gear into bar driving position, and means engageable by relative movement transversely of one of the aforementioned clutch gears, only when both are in neutral position, to control them for effecting rapid downward movement of the boring bar.

7. In a reboring machine, in combination with a base, a boring bar vertically reciprocable in the base, and carrying a head constituting a gear 20 casing upon its upper end, power means for effecting such reciprocation including a threaded shaft extending through said head, parallel to the boring bar, a nut threaded on said shaft, a driving gear keyed to the shaft, a differential gear loose on the shaft, and a common gear meshing with both said gears, and means to clutch the differential gear to the nut to effect differential rotation of the nut and threaded shaft, said clutch means being movable into neutral position, the driving gear having an extension engageable with the nut, the parts being so arranged, rotated, and disposed that in such neutral position the nut abuts said extension, which rotates with the shaft, on the side thereof toward which the nut tends to travel along the screw when held from rotation therewith, retardation in the nut's rotation thus tending to jam the nut against said element, whereby the nut increasingly tends to rotate at precisely the same 40 speed as the threaded shaft.

8. In a reboring machine, in combination with a base, a boring bar vertically reciprocable in the base, and carrying a head constituting a gear casing upon its upper end, a threaded shaft 45 extending through the said head and rotatable to effect reciprocation of the boring bar, a nut threaded on said shaft, and movable forward therewith as the shaft rotates while the nut is held from rotation or rotates at a speed slower than said shaft, a member keyed to rotate with said shaft and frictionally abutting the forward side of said nut, tending normally to increase its speed of rotation to equal that of said shaft as the nut moves forward along the bar to press 50 against said member, thus to check the forward movement of the nut, and means operable at will to effect positive relative rotation of the screw and nut to move said nut and said keyed member along the screw, thus to reciprocate the boring 60 bar.

9. In a reboring machine, in combination with a base, a boring bar vertically reciprocable in the base, and carrying a head constituting a gear casing upon its upper end, a right-hand threaded 65 vertical shaft journaled in the base and extending through the head, a nut threaded on said shaft, power means to rotate said shaft in a direction to move said nut downward along the shaft when the nut is held from rotation or rotates at a speed slower than said shaft, a driving gear keyed upon and rotating with said shaft, and disposed immediately below and frictionally abutting said nut, tending normally to rotate the nut therewith at the same speed as said shaft, and 70 means interconnectable between said driving gear

and said nut to effect rotation of the nut at a slower speed than said shaft and driving gear, thus to effect movement of said driving gear along said screw by pressure of the nut thereagainst.

10. In a reboring machine, in combination with a base, a boring bar vertically reciprocable in the base, and terminating at its upper end in a head constituting a gear casing, a power-driven screw journaled in the base and extending through the head, a nut threaded thereon, two differential gears, one constituting a driving gear and keyed to the screw, and the other loose thereon, a common gear in mesh with each differential gear, a gear-toothed sleeve slidable along and keyed to 15 rotate with the nut, a set of complemental clutch elements, one part on the loose gear and one part on the sleeve, engageable by lengthwise movement of the sleeve in one direction to advance the boring bar in a downward direction, 20 a pair of unequal gears meshing respectively with the driving gear and with the sleeve's gear teeth, a second set of complemental clutch elements movable to connect or to disconnect the unequal gears, whereby to rotate the nut in a different direction relative to the screw, when the latter clutch elements are connected, and to effect advance of the boring bar in the opposite direction, 25 and means controlling the engagement of the two sets of clutch elements, to interdict engagement of either set while the other set is engaged.

11. In a reboring machine, in combination with a base, a boring bar vertically reciprocable in the base, and terminating at its upper end in a head constituting a gear casing, a power-driven screw journaled in the base and extending through the head, a nut threaded thereon, two differential gears, one constituting a driving gear and keyed to the screw, and the other loose thereon, a common gear in mesh with each differential gear, a gear-toothed sleeve slidable along and keyed to rotate with the nut, a set of complemental clutch elements, one part on the loose gear and one part on the sleeve, engageable by lengthwise movement of the sleeve in one direction to advance the boring bar in a downward direction, 35 a pair of unequal gears meshing respectively with the driving gear and with the sleeve's gear teeth, a second set of complemental clutch elements movable to connect or to disconnect the unequal gears, whereby to rotate the nut in a different direction relative to the screw, when the latter clutch elements are connected, and to effect advance of the boring bar in the opposite direction, 40 and means controlling the engagement of the two sets of clutch elements, to interdict engagement of either set while the other set is engaged.

12. In a reboring machine, in combination with a base, a boring bar vertically reciprocable in the base, and terminating at its upper end in a head constituting a gear casing, a power driven screw journaled in the base and extending through the head, a nut threaded thereon and held in said head, three sets of clutch elements, each set including one part operatively connected to the nut to rotate therewith, and a complemental part en- 70 75

gageable with its first part, means operable by engagement of one such set of clutch elements to effect slow relative upward feed of the nut along the screw, thereby to effect slow downward feed of the boring bar, means operable by engagement of a second such set of clutch elements to effect relative downward feed of the nut along the screw, thereby to effect upward feed of the boring bar, and means operable by engagement of the 10 third such set of clutch elements to effect rapid relative upward feed of the nut along the screw, thereby to effect rapid downward feed of the boring bar.

13. The combination of claim 12, including also 15 means controlling the engagement of the several sets of clutch elements, and interdicting engagement of any other set while any given set is in engagement.

14. In a reboring machine, in combination with 20 a base, a boring bar vertically reciprocable in the base, and carrying a head constituting a gear cas-

ing upon its upper end, a threaded vertical shaft journaled in the base and extending through the head, a nut threaded on said shaft, power means to rotate said shaft in a direction to move said nut downward along the shaft when the nut is held from rotation or rotates in the same direction at a speed slower than said shaft, a member constituting part of said power means keyed upon and rotating with said shaft, and disposed immediately beneath and frictionally abutting said nut, tending normally to jam against the nut for rotation of the two jammed-together elements at precisely the same speed and in the same direction as the shaft, and clutch means interconnectable between said power means and the nut to effect rotation of the nut at a slower speed than said shaft and said keyed member, thus to effect movement of said keyed member along said shaft by pressure of the nut thereagainst.

CLARENCE T. ROTTNER. 20
